Primary Examiner — Richard Kearney*Assistant Examiner* — Liv C Anderson(57) **CLAIM**

The ornamental design for a light, as shown and described.

DESCRIPTION

FIG. 1 is a perspective view of a light showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof, shown in an environment of use.

The light is shown with a symbolic break in its length and the appearance of any portion of the light between the break lines form no part of the claimed design. The broken lines in the drawings depict portions of the light that form no part of the claimed design. The additional broken lines shown in FIG. 9 are for environmental purposes and form no part thereof.
